(57) CLAIM

The ornamental design for a double-ended wrench handle, as shown and described.

DESCRIPTION

FIG. 1 is a perspective view of a double-ended wrench handle showing my new design;

FIG. 2 is a top plan view thereof;

FIG. 3 is a bottom plan view thereof;

FIG. 4 is a right side elevation view thereof; and,

FIG. 5 is a left side elevation view thereof.

The front of the double-ended wrench handle forms no part of the claimed design; and, the rear of the double-ended wrench handle forms no part of the claimed design.

The broken line disclosure at the ends of the double-ended wrench handle shown in FIGS. 1-5 define the boundaries of the claimed subject matter, but form no part of it.
